UNITED STATES PATENT OFFICE.

RAYMOND H. SMICKLE, OF BELVIDERE, NEW JERSEY, ASSIGNOR TO INGERSOLL-RAND COMPANY, OF JERSEY CITY, NEW JERSEY, A CORPORATION OF NEW JERSEY.

DOUBLE-TUBE CONNECTION.

Application filed September 24, 1924. Serial No. 739,538.

To all whom it may concern:

Be it known that I, RAYMOND H. SMICKLE, a citizen of the United States, and a resident of Belvidere, county of Warren, State of New Jersey, have invented a certain Double-Tube Connection, of which the following is a specification accompanied by drawings.

This invention relates to fluid actuated percussive machines, and more particularly to rock drills of the hammer type which employ concentrically arranged tubes for conveying gaseous fluid and cleansing liquid to a drill steel for removing cuttings from a drill hole.

15 In order to effect the removal of cuttings from the drill hole most rock drills of the hammer type are equipped with a tube extending through the drill for conveying the cleansing liquid, in addition depending upon pressure fluid to escape past the piston and associated parts for the purpose of supplying pressure to the cleansing fluid.

20 This method of supplying pressure to the cleansing fluid, however, does not prove satisfactory under all conditions, due in part to the difficulty of providing for a certain predetermined supply of pressure fluid sufficient at all times for efficient cleansing of the drill hole. By employing two tubes concentrically arranged, one of which is adapted to convey gaseous fluid and the other a liquid, a continuous, controlled flow of both fluids may be obtained, thereby creating a greater pressure for removing cuttings from the drill hole.

25 One object of the invention is to securely hold concentrically arranged gaseous liquid and fluid conveying tubes in a rock drill of the hammer type.

30 Further objects will hereinafter appear in the following description and the accompanying drawings which illustrate the invention in one of its preferred forms.

35 Figure 1 is a longitudinal view, partly in section of a hammer type rock drill equipped with water and air tubes arranged in accordance with the practice of the invention,

40 Figure 2 is an enlarged longitudinal sectional view showing the details of the means for sealing and supporting the gaseous fluid and liquid conveying tubes in the back head of the rock drill, and

45 Figure 3 is an enlarged longitudinal sec-

tional detail view illustrating a modified method of supporting and sealing gaseous fluid and liquid conveying tubes in the back head of a rock drill.

50 Referring to the drawings, the invention is shown embodied in a rock drill comprising a cylinder A, with front head B supported in the forward end of said cylinder, and a back head C separated from said cylinder by suitable rotation ratchet mechanism D and a back cylinder washer E; all being held in operative relation by the usual side bolts (not shown). A front cylinder washer F forming a closure of the forward end of the cylinder A is held in position by means of the front head B. A 55 hollow drill steel G extending through a chuck key H, and held in alignment by a chuck jaw J is adapted to receive the impact blows of a reciprocating piston K.

55 Distribution of the motive fluid is preferably effected by means of a valve (not shown) of any suitable type, operating in the valve chest L and in communication with a throttle valve M in the back head C, operated by means of a throttle lever O.

60 In order to keep the drill steel free in the drill hole, rotative means are provided, and to this end there is employed a rifle bar P which is adapted to slidably engage a rifle nut Q in the rearward end of the hammer piston K. The nose R of the hammer piston is fluted and in slidable engagement with a chuck nut S in the chuck T, rotatively engaged with the chuck jaw J preferably by means of clutch members U and V. In this instance wings W of the hollow drill steel G interlock with the flats X of the recess Y for preventing relative 65 rotative movement between the chuck jaw J and the drill steel.

70 In accordance with the invention, an air conducting tube Z having a conical end a is shown supported in a correspondingly conical bore b in the back head C, the tube Z being adapted to extend through the drill to a point preferably a slight distance from the impact receiving end of the drill steel G when the drill steel is in its uppermost position. A liquid conducting tube c of smaller diameter than the said air tube Z has a coniform rearward end d and is arranged within said air tube, preferably being of sufficient length to extend 75

for a short distance within the bore of the drill steel G. The tube c is supported in the bore e of the tube Z, and its end d preferably extends slightly beyond the end a of the tube Z. The end f of the tube c is in this instance shown tapered and designed to be of sufficiently smaller cross sectional area than the hollow bore of the drill steel G to leave room for the air under pressure also to be admitted into the hollow bore of the drill steel to the drill hole.

The length of contact between the end a of the tube Z and the bore b at the back head C is designed to be of sufficient area to insure a suitably fluid tight joint. Likewise, the end d of the tube c is arranged to conform to the bore e of the tube Z and to be of a suitable length to provide sufficient sealing area at all times.

In operation, due to hard usage which a machine of the hammer type receives, inefficient sealing is likely to occur between the several parts due to natural wear, thereby permitting cleansing fluid to escape to the movable parts, washing away lubricant and causing excessive wear. In order to overcome this difficulty and to insure proper sealing contact at all times, a resilient member, in this instance a compression coil spring g is employed, said coil spring being arranged within a recess h of the water plug j, one end of the spring being adapted to bear against the roof of recess h and the other end against a hollow cylindrical member k, the cylindrical member k being arranged adjacent to the end d of the tube c. In this manner due to the direct contact of the parts k, Z, and c and to the compressive force of the spring g, a fluid tight joint is at all times maintained thereby eliminating undue wear and the need of inspection and adjustment on the part of the operator.

Near the juncture of the conical end a and the tube Z are arranged a plurality of ports m adapted to provide a passage for the pressure fluid from an angular groove o in the back head C to the hollow bore of the tube Z, the said annular groove being in communication with a source of supply (not shown) by means of a passage p. A groove q in the water plug j is arranged to communicate with the passage r by means of a recess s, thus providing a passage for the cleansing fluid (source of supply not shown) to the back head cap t from whence it is preferably adapted to flow through a restricted port u communicating with the liquid conveying tube v through the hole v, the recess h of the water plug j and the hollow cylindrical member k. In this manner a direct and constant flow of both pressure fluid and cleansing liquid may be provided, the two fluids intermingling in the hollow bore of the drill steel G at the end f of the tube c, thereby providing a uniform flow of

cleansing liquid under pressure for removing cuttings from the drill hole and allaying dust.

However it is to be understood that either pressure fluid or cleansing liquid may be employed separately if desired.

In Figure 3 is shown a modified method of securing cleansing liquid and pressure fluid tubes in the back head of a rock drill. In this instance the pressure fluid tube Z has a coniform rearward end a, adapted to conform to a conical bore b in the back head C. Within the pressure fluid tube Z a cleansing liquid tube w of smaller cross sectional area than the air tube is concentrically arranged. The conical end y of the tube w is preferably formed flush with a corresponding end of the tube Z. In order to secure the air tube within the back head C, there is provided a screw threaded water plug z in engagement with the back head C by which means a reduced end 2 of the water plug z may be brought to bear firmly upon the end a of the air tube. In the recess 3 of the water plug z there is disposed a compression member 4, preferably a coil spring, adapted to bear at one end against the roof of the recess 3, the other end of the spring bearing against a hollow cylindrical member 5, of smaller diameter than the outside diameter of the conical end y of the liquid conducting tube w on which it is adapted to bear. In this manner the tube Z is rigidly secured in place by manually adjustable means, and the tube w is held in sealing position by the compressive force of the coil spring 4. However, should wear occur between the sealing surfaces of the end d and the recess 3 or should the water plug z not be adjusted to its proper bearing position, the coil spring 4 will exert sufficient pressure to form a fluid tight joint, thereby holding the water and air tubes in sealing positions and preventing leakage of cleansing fluid to the movable parts of the rock drill thus leaving the lubricant on these parts unimpaired.

I claim:

1. In a fluid actuated rock drill, the combination of a cylinder with a back head, a coniform seat in said back head, a reciprocating hammer piston in said cylinder, a pair of concentrically arranged conical ended fluid conveying tubes extending through the cylinder, and resilient means for holding the conical end of one of said tubes against said coniform seat and for holding the conical end of the other said tube in fluid tight contact with the corresponding end of the first said tube.

2. In a fluid actuated rock drill, the combination of a cylinder with a back head, a coniform seat in said back head, a reciprocating hammer piston in said cylinder, a pair of concentrically arranged conical ended

ed fluid conveying tubes extending through the cylinder, a spring for holding the conical end of one of said tubes against said coniform seat and for holding the conical 5 end of the other said tube in fluid tight contact with the corresponding end of the first said tube, and an adjustable plug for varying the tension of said spring.

3. In a fluid actuated rock drill, the combination of a cylinder with a back head, a 10 coniform seat in said back head, a reciprocating hammer piston in said cylinder, a pair of concentrically arranged conical ended fluid conveying tubes extending

through said cylinder, a compression spring 15 for holding the conical ends of said tubes in fluid tight contact with each other and for holding the conical end of the outer of said tubes in fluid tight contact with the coniform seat, an adjustable plug screwed 20 into the back head for varying the tension of said spring, ports and passages for conducting fluids to the interior of said tubes, and means for sealing the back head to prevent leakage of fluid therefrom. 25

In testimony whereof I have signed this specification.

RAYMOND H. SMICKLE.
